SAFETY RAZOR

Arthur W. McGown, Challis, Idaho

Application December 5, 1936, Serial No. 114,499

1 Claim. (Cl. 30—68)

This invention relates to safety razors and has for an object to provide a safety razor having a spring pressed spindle provided with jaws for detachably mounting the cap, the spindle being movable longitudinally of the tubular handle of the safety razor to project the blade and the cap away from the guard so that the blade may be easily cleansed by simply reciprocating the spindle up and down with the blade immersed in water, without touching the blade with the hands.

With the above and other objects in view the invention consists of certain novel details of construction and combinations of parts herein-after fully described and claimed, it being understood that various modifications may be resorted to within the scope of the appended claim without departing from the spirit or sacrificing any of the advantages of the invention.

In the accompanying drawing forming part of this specification,

Figure 1 is a side elevation of a safety razor constructed in accordance with the invention.

Figure 2 is a longitudinal sectional view through the parts shown in Figure 1 with the spindle and cap shown dotted in projected position.

Figure 3 is an enlarged cross sectional view taken on the line 3—3 of Figure 2.

Referring now to the drawing in which like characters of reference designate similar parts in the various views, 10 designates the cap which is provided with positioning pins 11 which pass through openings 12 in the guard 13 in the usual manner. The cap is provided with a stud 14 having a substantially rectangular head 15 best shown in Figure 3, the stud being centered between the positioning pins 11.

The guard 13 is formed integral with a tubular handle 16 which slidably receives a spindle 17 which is substantially twice the length of the handle. The spindle is provided in one side with a longitudinal guide groove 18 which is disposed near the outer end of the spindle and receives a guide pin 19 which is threaded through an opening in the tubular handle and through a bushing 20 inserted in the end of the tubular handle which bushing provides a bearing for the spindle. Sliding movement of the spindle, when the handle is grasped between the fingers and the thumb placed upon the outer end of the spindle, is limited by contact of the pin 19 with the ends of the groove 18.

A helical spring 21 is sleeved upon the spindle within the tubular handle and is confined under tension between a stop collar 22 on the spindle and a shoulder 23 formed in the bore of the han-

dle near the guard. The spring returns the spindle to neutral position after each forward movement thereof due to pressure of the operator's thumb.

The spindle terminates in a pair of jaws 24 which are cut away at their inner ends to provide a recess 25 to receive the head 15 of the stud 14. The shoulders 26 formed in the jaws at the outer end of the recess 25 hook over the head 15 of the stud and detachably secure the cap to the spindle. When the spindle is moved outwardly the cap may be rotated through part of a turn to dispose the head 15 so as to disengage from underneath the shoulders 26 and pass outwardly between the jaws to permit removal of a used blade. Since the cap is concave transversely as shown in Figure 1 the jaws will strike the cap if an attempt is made to remove the head of the razor by sliding it transversely between the jaws thus rendering necessary a partial rotation of the head as a preliminary step to removal from the stem.

In operation, after use of the razor in shaving in order to thoroughly cleanse the razor, it is simply necessary to invert the razor from the position shown in Figure 2 and submerge the cap, blade and guard in a container of water and then reciprocate the blade and cap up and down by coaction of the thumb and fingers of the hand and the spring 21. During such reciprocation the cap and blade will move freely up and down through a stroke equal to the length of the guide groove 18 and thus the blade will be thoroughly cleansed in minimum time without need of the operator's fingers touching the blade.

It will be further pointed out that by releasing the spring 21 and then turning the cap 10 slightly and allowing the unperforated portion of the guard to come to rest on the positioning pins 11, the razor and blade can be cleaned at any time during the operation of shaving, by inverting the same in water and moving the razor up and down. The blade moves up and down freely or independently between the cap 10 and the guard 13 and in this way is thoroughly cleansed and need not be wiped or dried as after cleaning and removal from the water the air has free access to all parts. Should the blade accidentally rotate about the upper end of the spindle 17 when cleansed, it is an easy matter to engage the blade with the guide pins 11 preliminary to assembling the razor for use.

From the above description it is thought that the construction and operation of the invention

will be fully understood without further explanation.

What is claimed is:

- 5 A safety razor comprising a cap, spaced positioning pins on the cap, a guard having openings removably receiving the pins, a stud on the cap centered between the pins and terminating in a substantially rectangular head, a tubular handle integral with the guard, a spindle slidably mounted in the handle, said spindle being substantially twice the length of the handle and projecting from the outer end of the handle, there being a longitudinal groove in the spindle exposed beyond the handle, a bushing in the end 10 of the handle forming a bearing for the spindle, a guide pin threaded through the handle and

bushing and projecting into said groove to limit sliding movement of the spindle, a collar on the spindle adjacent to the bushing, a shoulder formed in the bore of the handle near the guard, a helical spring sleeved on the spindle near the handle and confined under compression between the collar and the shoulder, and a pair of jaws formed on the inner end of the spindle detachably receiving the head of the stud, pressure of the operator's thumb against the projecting end of the spindle while the handle is held stationary serving to move the cap to disengage the positioning pins from the guard and permit the cap being spaced from the guard to facilitate cleaning of the razor blade. 15
